INVENTOR:

HERBERT S. MILLS,
By Dyerforth, Lee, Chitton and Willis, ATTYS.

UNITED STATES PATENT OFFICE.

HERBERT S. MILLS, OF CHICAGO, ILLINOIS.

MOVING-PICTURE MACHINE.

No. 916,751.

Specification of Letters Patent. Patented March 30, 1909.

Application filed October 3, 1908. Serial No. 456,050.

To all whom it may concern:

Be it known that I, HERBERT S. MILLS, a citizen of the United States, residing at Chicago, in the county of Cook and State of Illinois, have invented a new and useful Improvement in Moving-Picture Machines, of which the following is a specification.

The object of my invention is to facilitate the feeding of the film under the feeding action of the intermittent "movement" in a moving-picture machine by providing, to cooperate with means on the machine for tautening the film where it traverses the lens, means operating to free the film with each action of said movement.

In the accompanying drawing, Figure 1 is a view showing in front elevation a machine for exhibiting moving pictures, provided with my improvement, and Fig. 2 is a section on line 2, Fig. 1.

The machine selected for illustrating my improvement, and, in fact, with reference to which I have more particularly devised it, is that shown and described in the patent of H. K. Sandell, for a moving picture machine, No. 890,936, dated June 16, 1908, from which the present drawings differ only in minor details.

The frame 3, provided with a cheek-ex- tension 4, has the lens-barrel 5 on it to register its tapering end with the opening 6 in the frame for directing light into the lens. The drive-shaft 7 journaled in the frame carries on one end a master-gear 8 meshing with a gear 9 on a shaft 10 journaled in the upper part of the frame and carrying the guiding-barrel 11 for the film 12. This barrel is geared at one end to a shaft carrying, in engagement with the barrel 11, a sprocket-barrel 14 for engaging the edge-perforations of the film in continuously feeding the latter, the shaft 13, on which the barrel is rotatable, being rigidly mounted on a swinging arm 15. On the cheek 4 is pivotally suspended at 16 a yoke 17 formed as a rigid part of a rectangular film-clamping spring-frame 18 which hangs over the light-admitting opening 6. This opening is flanked by inserts 19 formed of steel strips with which the sides of the frame 18 coincide, and in these sides, near their upper ends, work with slight longitudinal play, limited by the heads on their outer ends, studs 20 carrying steel strips 21 to clamp the film-edges against said inserts for maintaining the film in taut condition

where it covers the opening 6. Another stud 22 extends from about midway between the ends of each frame-side through a boss 23 formed thereon and in which is confined against the respective strip 22 a spiral spring 24 adjustable as to its tension by a screw 25 working in the boss.

In the particulars described and in all other particulars the construction of the frame 18 corresponds substantially with that of the film-clamping frame of the aforesaid patent, including a latch 26 pivoted on the frame 3 to releasably engage an ear 27 on the clamping-frame or gate to lock the latter in its film-clamping position. The intermittent "movement" 28 shown in the drawings is also the same as that of the aforesaid patent, so that its construction and operation in intermittently feeding the film need not be minutely described herein. The film passes from the coil thereof (not shown, but all as shown and described in United States Letters Patent No. 887431, dated May 12, 1908) about the sprocket 14, and between the latter and the barrel 11, adjacent to which it forms the loop 29, thence past the spring-pressed guide-barrel 30 across the opening 6 between the inserts 19 and frame 18 and between spring-pressed rollers 30¹ at the bottom of the clamping-frame and the sprockets 31 on the shaft 32 of the star-wheel member of said movement, all as described in said first-named patent.

On the shaft 33 of the driving-member of the movement 28, and which is geared to the shaft 7, as shown, is provided a cam 34 engaging with an anti-friction roller 35 journaled in the lower end of an arm 36 pivotally suspended on the shaft 7, said arm having fingers 38 extending into abutting engagement with the clamping strips 21 near their lower ends. With this device, which constitutes the feature of my invention, each time the movement feeds by its intermittent action the film across the lens-barrel at the opening 6, at the beginning of the complete rotation of the driving-member on the shaft 33, the cam 34 turns the arm 36 to force the strips 21, against the resistance of the springs 24, away from the film-edges, thereby releasing the film from the clamping engagement therewith of the gate and permitting the movement to feed it freely and without dragging, thereby greatly saving the wear on the film.

What I claim as new and desire to secure by Letters Patent is—

1. In a moving-picture machine, the combination with a frame supporting guiding-
5 means for the film and containing an opening for directing light into a lens-barrel on the frame, of a spring-pressed film-clamping gate suspended on the frame to hang over said opening therein and having spring-pressed strips movably 25 supported on its sides to engage said inserts, a star-wheel movement and driving means therefor on the frame for intermittently feeding the film past said opening, a cam on the driving-member of said movement, and a suspended swinging arm on the frame engaging at its free end with said 30 cam and having fingers extending from it into engagement with said gate, for the purpose set forth.

2. In a moving-picture machine, the combination with a frame supporting guiding-
10 means for the film and containing an opening

for directing light into a lens-barrel on the frame, of insert-strips in the sides of said opening, a film-clamping gate suspended on the frame to hang over said opening therein and having spring-pressed strips movably 25 supported on its sides to engage said inserts, a star-wheel movement and driving means therefor on the frame for intermittently feeding the film past said opening, a cam on the driving-member of said movement, and a 30 suspended swinging arm on the frame engaging at its free end with said cam and having fingers extending from it against said strips in opposition to their spring-pressure, for the purpose set forth.

HERBERT S. MILLS.

In presence of—

K. M. CORNWALL,
R. A. SCHAEFER.
